DESIGN FOR A SCALE CASING

Harold L. van Doren, Toledo, Ohio, assignor to
Toledo Scale Manufacturing Company, Toledo,
Ohio, a corporation of New Jersey

Application November 18, 1937, Serial No. 72,993

Term of patent 14 years

To all whom it may concern:

Be it known that I, Harold L. van Doren, a citizen of the United States, residing at Toledo, in the county of Lucas and State of Ohio, have invented a new, original, and ornamental Design for a Scale Casing, of which the following is a specification, reference being had to the accompanying drawing forming a part thereof.

Figure I is a view in perspective showing the

front and one side of the scale casing of my new design; and

Figure II is a view in perspective showing the back and the other side of the scale casing of my new design.

I claim:

The ornamental design for a scale casing as shown.

HAROLD L. VAN DOREN.
